Primary Examiner — George D Kirschbaum*Assistant Examiner* — Jennifer Watkins(74) *Attorney, Agent, or Firm* — Thompson Hine LLP(57) **CLAIM**

The ornamental design for a knee wrap, as shown and described.

DESCRIPTION

FIG. 1 is a perspective view of a knee wrap showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a perspective view thereof with the pocket thereof in an open position.

The broken lines showing stitches on claimed surfaces is for the purpose of illustrating portions of the article and form no part of the claim. The broken lines in FIGS. 1 and 6-8, with respect to the inseam padding, illustrate environmental subject matter and form no part of the claim.

1 Claim, 7 Drawing Sheets(56)
